UNITED STATES PATENT OFFICE.

JUDD E. HAMMOND, OF MUNDAY, TEXAS.

VANITY MANICURE BOX.

Application filed March 21, 1925. Serial No. 17,156.

To all whom it may concern:

Be it known that I, JUDD E. HAMMOND, a citizen of the United States, residing at Munday, in the county of Knox and State of Texas, have invented certain new and useful Improvements in Vanity Manicure Boxes, of which the following is a specification.

This invention relates to improvements in vanity sets and refers more particularly to the novel construction and arrangement of the parts thereof.

The primary object of the invention is to provide an improved kit for manicuring finger nails, the device containing a nail file, nail polisher and compartment holding nail polish, arranged in compact form.

Another object of the invention is to provide a device of this nature which will be neat and attractive as well as practical for the purpose intended.

The invention will be more fully understood by reference to the following description, taken in connection with the accompanying drawing, forming part hereof in which:

Figure 1 is a top view of the device.

Figure 2 is a bottom view.

Figure 3 is a side view, and

Figure 4 is a vertical sectional view on line 4—4 of Figure 1.

Referring more particularly to the drawings, the kit or vanity set comprises a box with lid 2, the latter hinged at 3 to the box 1 and provided with a snap arrangement 4 to lock the lid in place. The box and lid are constructed of metal, silver-plated or nickel-plated, or may be constructed of any metal suitable for the purpose and not too expensive for manufacturing the article.

On the bottom of the box is arranged a nail file 5 pivoted by a button 6 to be swung to various positions as indicated for instance by the dotted lines in Figure 2 and when not in use the nail file may have its position under the box as shown in full lines.

Inside the bottom portion of the box is arranged a supply of powder 7 for polishing the nails, and upon the powder and separating it from the upper part of the box is

a circular perforated disk 8^a of celluloid or other suitable material. The disk being perforated permits the powder to be fed out through the perforations 9^a as the box is rotated in polishing the nails.

As a buffer for polishing the nails there is provided a rubber cushion 8 with a chamois skin covering 10 and having a central opening 9, the cushion being pressed down into the box 1 through the large opening in the lid and held in place by the flanges 2^a on the cover 2. The cushion or buffer 8 may be of rubber or other material.

It will be noticed that this arrangement provides two distinct compartments in the box, one for containing the buffer and the other for the nail polishing material.

The kit is relatively small and is operated by inserting the finger 11 into the opening 9 against the disk 8^a and rotating the box. The rotation will cause the powder 7 to be automatically fed outward against the finger nails. The nail file, as is obvious, may be moved to any desired position to file the finger nails.

It should be understood that the invention is not limited to the particular arrangement and construction shown herein, but may be modified and changed to come within the scope and meaning of the following claims:

1. A vanity kit for manicuring the finger nails, comprising a box with a hinged lid and a flange and an opening in the lid to receive a buffer, a perforated disk beneath the buffer, a powder compartment between the disk and the bottom of the box and a movable file for the nails on the bottom of the box.

2. A vanity box and finger nail manicure set, comprising a box with a hinged lid, an opening in the lid to receive a nail buffer, flanges on the lid to hold the buffer in place, said buffer comprising a cushion with a roughened covering to polish the nails and a central opening traversing the cushion from top to bottom, a perforated disk under the cushion, the perforations in alignment with said opening in the cushion, a compartment formed by the disk and the bottom of the box.

the box for nail powder and a nail file on the bottom of the box.

3. A vanity finger nail manicure set comprising a box with a hinged lid with an opening, a powder compartment, a powder feeding disk and a buffer in the box, said buffer having an opening disposed over the

disk, said buffer extended outside the lid of the box and held in place by flanges on the lid; and a movable nail file on the bottom of the box.

In testimony whereof I have signed my name to this specification.

JUDD E. HAMMOND.
